COUNTING MECHANISM

Harvey N. Bliss, Hartford, Conn., assignor to
Veeder-Root, Incorporated, a corporation of
Connecticut

Application January 10, 1930, Serial No. 419,934

6 Claims. (Cl. 235—102)

My invention relates to counting mechanisms. It has for its object to provide an improved counting mechanism and more particularly such an improved mechanism especially adapted to 5 count accurately all of the ribbon advancing strokes of a typewriter, tabulator, bookkeeping machine, or the like. A further object is to provide such a counter wherein irrespective of differences in the length of the strokes of the different 10 keys and of the space bar, or a variation in the touch of different operators, an accurate count is obtained. A still further object of my invention is to provide such a mechanism in which the load placed on the keys or space bar is minimized 15 in such manner as to reduce the effort required on the part of the operator using the machine. Other objects of my invention are to provide such an improved mechanism which is adapted to be easily installed and operatively connected to an 20 operating part of the machine without disturbing the machine adjustments or altering the machine, and which further in its various forms is adapted to be applied to a wide range of machines and to be economically manufactured. These 25 and other objects and advantages of my improved construction will, however, hereinafter more fully appear.

In the accompanying drawings I have shown for purposes of illustration several embodiments 30 which my invention may assume in practice.

In these drawings:

Figure 1 is a front view of one form of my improved mechanism shown in position on a typewriter or tabulator, only the supporting and actuating connections of the machine being shown. 35

Figure 2 is a side view of the mechanism shown in Figure 1 with the machine frame shown in section.

Figure 3 is an enlarged partial side view of 40 the structure shown in Figure 2.

Figure 4 is an enlarged partial side view similar to Figure 3, but showing the parts in another position.

Figure 5 is a detail view looking in the direction 45 of the arrows 5—5 in Figure 4.

Figure 6 is a longitudinal sectional view through the counter clutch mechanism.

Figure 7 is a transverse sectional view through the ball clutch mechanism included therein, the 50 view being taken on a line 7—7 of, Figure 6.

Figure 8 is a similar sectional view on line 55 8—8 of Figure 6 showing the ratchet clutch mechanism.

Figure 9 is a front view similar to Figure 1, but showing a modified construction.

Figure 10 is a side view of the structure shown in Figure 9 with certain parts of the frame and supporting structure in section.

Figure 11 is an enlarged partial side view of

the structure shown in Figure 10 when viewed from the opposite side.

Figure 12 is an enlarged partial side view similar to Figure 11, but showing the parts in another position. 5

Figure 13 is a front view similar to Figure 1, but showing a further modified construction.

Figure 14 is a side view of the structure shown in Figure 13, the dotted lines showing another position of the parts and certain of the parts being shown in section. 10

Figure 15 is a plan view of the structure shown in Figures 13 and 14.

In all of these forms of my invention, although the latter in certain of its phases is not limited thereto, I prefer to use a counter of the type disclosed in U. S. Patent 1,873,079 invented by C. H. Veeder and having actuating mechanism including combined ratchet actuating and friction retaining mechanism, since I find that my combination of such a counter with the key or space bar operated mechanism of a machine such as a typewriter, tabulator, or the like enables new and advantageous results to be obtained in the art of counting the ribbon advancing strokes of such 25 machines.

Referring first to this counter mechanism per se, it will be noted that the same is herein carried in a suitable casing 1, having a usual reading aperture 2 through which a series of rotatable 30 numeral wheels 3 are visible in a usual manner. These wheels 3 are also operatively connected in a usual manner through mechanism (not shown) so that they will be actuated successively upon predetermined operations of a protruding 35 axial shaft 4. As usual in this Veeder type of counter, an actuating arm or lever 5 is also carried by the reduced outer end of the shaft 4, and a combined ratchet and ball clutch mechanism is provided between the lever 5 and the 40 shaft 4.

More particularly considering the Veeder combined clutch mechanism which is shown in Figs. 6, 7 and 8, it will be noted that the lever 5 is 45 carried on a squared hub 6 on an internally toothed member 7 rotatable on the reduced outer end of the shaft 4 and adapted to co-operate with internal radially disposed pawls 8 pivotally mounted on an intermediate member 9 and normally held in engagement with the teeth on the member 7 by springs 10 likewise carried on the intermediate member. As shown, this intermediate member 9 is also preferably fitted on a polygonal portion 11 on the shaft 4 inside the 50 reduced end thereof. Associated with this ratchet clutch mechanism is also co-operating ball clutch retaining mechanism. This includes a series of balls 12 received in the opposite face of the intermediate member 9 and pressed out 55 60

by coil springs 13. These balls engage with cam surfaces 14 on a co-operating member 15 which is also fixed upon the polygonal portion 11 of the shaft 4, while the balls are also supported in position by a plate 16 in a usual manner and in their retaining position engage a retaining cup 17 fixed to the counter casing. It will thus be evident that at each oscillation of the lever 5, the shaft 4 will receive through the driving pawl 10 clutch including the member 1, pawls 8 and intermediate member 9, an advance movement through a definite division of a complete movement of rotation, and, also, that after each such advance movement, it will be retained in its advanced position during the next backward movement of the actuating lever 5 by the immediate engagement of the balls with the retaining cup 17.

In the form of my invention illustrated in Figures 1 to 5 inclusive, it will be noted that such a counter as described has its reading aperture 2 disposed substantially at 45 degrees to a depending bracket portion 20. This bracket 20 in turn is attached by suitable screws 21 to an upstanding portion 22 of a bracket 23 which also has an upstanding lower end fixed to the machine frame 24 by suitable screws 25, and an intermediate inclined portion 26 underlying the counter and herein substantially spaced below the same. It will also be noted that the portion 22 of the bracket is provided on the side adjacent the lever 5 with spaced lugs 27 forming a notch 28 between them in which the free end of the lever 5 is movable within the maximum limits established by the lugs. Herein the latter are spaced apart sufficiently to allow the lever 5 to travel far enough for the pawls 8 to pick up one tooth of the ratchet member 7 but not far enough to pick up two teeth. Thus, it will be noted that the counter is advanced a predetermined fraction of a unit, herein a tenth, upon each oscillation of the member 5 between the lugs 27, it being understood that a usual form of counter is used which is geared in any suitable ratio, herein to register five figures for a complete revolution so that, when operated by a fifty toothed ratchet, it accordingly counts one for every ten teeth of the ratchet. Pivotal connected to the lever 5 at a point between its axis and the lugs 27 herein more closely adjacent the latter, is also an operating member 29 which is operatively connected to a part of the machine movable with each operative stroke, i. e. of any ribbon advancing stroke such as the printing keys or the space bar through mechanism hereinafter described.

Considering this latter mechanism more specifically, it will be noted that the member 29 has a lateral extension 30 on its lower end which is received in a vertically elongated slot 31 in the outer end of an arm 32, the opposite end of which is in turn suitably attached as by a screw 33 to the usual spring returned ribbon feed shaft 34 of the machine. The member 29 is thus adapted to be depressed manually when any key or the space bar of the machine is operated, and automatically elevated by the machine. It will further be noted that the slot 31 is disposed transversely of the arm 32 and lengthwise of the member 29. The latter also carries intermediate its ends a clip 35 fixed thereon. This clip has means on its lower end for positioning it on the member 29 comprising a depending extension 36 which receives the extremity of the portion 38 projecting through the arm 32. On its upper end the

clip 35 also has a lateral extension 37 projecting out over the end of the member 32 and connected thereto by a light coiled spring 38 normally operative to cause portion 30 to remain at the bottom of the slot 31.

Considering the operation of the device it will be evident that upon the actuation of any key or the space bar, the member 32 will be oscillated in such manner as to cause the lever 5 to be moved between the lugs 27, for example, from the position shown in Figure 3 to the position shown in Figure 4, each time that this member 32 is moved downward by the depression of a key or the space bar. This movement of the member 32 will be transmitted through the spring 38 to the member 29, and thereby cause the lever 5 to swing downward, whereas, after each stroke, the parts will be automatically returned under the action of the spring returned ribbon feed shaft 34 to the position indicated in Figure 3, the arm 32 acting directly on the portion 30 of member 29. Here, it will also be noted that the downward movement of the lever 5, merely requires dragging of the pawls over the ratchet. On the other hand, the upward stroke, which herein is the registering stroke, and thus requires more power, is effected by the power of the machine as the latter automatically raises the arm 32. Thus, effort on the part of the operator is minimized while the actual work is done by the machine, the spring for returning the key or space bar operated mechanism ordinarily having sufficient excess power to operate the counter without change. Further, due to my improved construction, only such a small portion, estimated at five percent, of the excess power of the ribbon feed of the machine is required to operate the counter on its registering stroke as to be well within the margin of safety required by that mechanism. It will also be observed that if the operator strikes a key hard, or if any key or other connected part has a longer stroke, the member 32, by reason of the slot 31, has a limited free movement relative to the portion 30 of the member 29. At the same time, it will be noted that, upon the engagement of the lever 5 with the bottom lug 27, the operation of the machine is in no way hindered, a full operation of the ribbon feed shaft instead being permitted. Attention is also directed to the fact that the member 32 during its automatic upward movement, engages and positively lifts the member 29 to effect the return or registering stroke, and to the further fact that this registering stroke being thus effected by the machine, it is always the same. Thus, irrespective of how hard the keys are struck or of the inertia of the parts, there is no danger of an overthrow of the pawls. It will also be evident that by the use of my over-travel structure in the connection between the counter and the machine, in conjunction with the positive stops provided by the spaced lugs, an accurate count is assured automatically and without need for a compensating adjustment, regardless of the varying stroke inherent in the machine. Further, the spring 38 co-operates with the usual spring, not shown, which automatically returns the shaft 34, and assists the latter in returning the arm 32 to its initial or up position during that part of any stroke in which the arm 32 has moved beyond the limit imposed on lever 5 by the lower stop 21.

In my improved construction, I have also taken advantage of the single dragging over operation of the pawls and of the shorter stroke required

in a counter of the type having a combined ratchet actuating and ball retaining clutch, and so combined such a counter with the key stroke operated mechanism of a machine such as a typewriter or the like, which inherently has a very limited amount of motion and power available, that the load upon the keys is minimized and that the smaller amount of power required for registering is supplied by the machine either 5 from power stored when the carriage is shifted, or from the excess power available in the key or space bar operated mechanism. It will of course also be evident that due to my improved construction of counter actuating and controlling 10 means, my improved mechanism will register accurately on each operative stroke on the machine. It will also be evident that it is adapted to do this despite variations in stroke of any of the stroke operated parts of a particular machine, as, for example, where the keys, or certain of the same, and the space bar have strokes of different length, the operation of any of these 15 resulting in the operation of the same automatically returnable member on the machine. Attention is also directed to the fact that my 20 improved mechanism is also adapted to accurate operation despite the fact that this member may have operative strokes of different length. Thus it will be evident that the mechanism is adapted 25 to produce accurate results not only when applied to any given machine, but when applied on different machines having different characteristics, and also when a given machine or 30 various different machines are operated by different operators each having a wholly different touch. It will further be noted that through the 35 use of a combined ratchet actuating and ball retaining clutch it is made possible to eliminate the inaccuracy inherent in a friction actuating 40 clutch when wear occurs, which would completely destroy the effectiveness of the whole device as a counting means for counting the operative strokes of a writing machine. Moreover, 45 it is also possible to eliminate any inherent inaccuracy in a ratchet retaining clutch capable of a slight subtraction before each retaining action. It is also possible to eliminate all necessity 50 for the minute accuracy in locating the counter on the bracket with respect to the notch in the latter which serves as stop means for the lever 5, which would be required if a ratchet retaining clutch were used instead of the ball retaining clutch. Thus the holes in the bracket for 55 attaching the counter need be tapped only in approximate location with respect to the notch in the bracket, and the notch itself need not be minutely accurate, provided it is of a proper size to allow the lever 5 to travel far enough for the 60 pawls to pick up one tooth of the ratchet member 7, but not far enough to pick up two teeth. These and other advantages of my improved construction will, however, be clearly apparent to those skilled in the art.

Referring to the modification shown in Figures 9 to 12, it will be noted that the structure is essentially similar to that previously described. Here, however, it will be noted that, whereas in the first construction the frame of the counter unit was disposed at an angle of approximately forty-five degrees to its bracket, in this construction the same is disposed at right angles to the bracket. The latter is also provided with oppositely extending vertically disposed projections 75 40 which carry screws 41 extending therethrough

and through a part of the machine frame 42 to which they are suitably attached by a back plate 43, threaded to receive the same. It will also be noted that herein apertures 44 slightly larger than the screws are provided in the frame, and that an adjustable stop plate 45 is disposed between the bracket and the frame, and provided with slotted ends 46 adapted to permit adjustment relative to the screws 41. This plate is also provided at right angles to its body with lugs 47 forming a notch 47a for the lever 5. It will also be noted that instead of a short member pivoted at one end, such as the member 32, an elongated member 48, corresponding to the member 32 and likewise automatically returned by 15 the machine, is provided. This member 48 is pivoted at 49 substantially midway between its ends and beneath the support 50 for the frame member 42, and also pivotally connected at its inner end at 51 to the escapement mechanism of 20 the machine operative with each key stroke or space bar stroke. It will here also be noted that the pivot 49 is carried on a bracket 52 supported beneath the portion 50 in any suitable manner and attached to the machine frame as by screw 25 53.

As regards the operation of this modified structure, it will be evident that it is essentially similar to that previously described. It will also be observed that in this construction, besides 30 serving as an over-travel connection, the spring 38 is especially effective in helping to return the member 48 to its upper position, if, as is apt to be the case the member 48 has exceeded the 35 range of movement of the counter lever 5. Attention is, moreover, directed here to the fact that in this construction an adjustment is obtainable by sliding the notched plate 45 up or down to take care of any variations in different machines when attaching the counter to the 40 machine. It will also be noted that this adjustment is made possible by the use of the ball retaining clutch and that such an adjustment would be impossible if a ratchet retaining clutch were used in lieu thereof since then an accurate 45 fixed location of the plate in angular relation to the retaining pawl of the counter would be required.

In the modified construction shown in Figures 13 to 15, it will also be noted that while fundamentally the same construction is provided, the same distinguishes from those heretofore described in certain particulars. In this construction the bracket and counter is essentially the same as that heretofore described, but a different 50 support is provided between the bracket and the machine frame. More particularly, the counter bracket 60 is attached by screws 61 to a bracket member 62 carrying an upstanding projection 63 having lugs 64 thereon forming a lever notch 65, 60 and also having an angular disposed portion 66 and a connected end portion 67 which is suitably attached to the machine frame 68 by screws such as the screw 69. Also, as regards the actuating connection for the member 29 it will be noted that 65 the latter member is connected to the free end of a twisted clip member 70 having its other end bent over as indicated at 71 and attached as by a screw 72 to a spring biased rock shaft 73 of the machine which is rocked against its bias upon 70 operation of any key or of the space bar. In this construction it will also be noted that the spring 38 has its point of connection of the member 70 spaced farther from the slot 31 than in the previous constructions, it being found that this angu- 75

lar disposition of the spring gives a most effective return action without stiffening the spring in such manner as to interfere with the over-travel. Obviously, the operation of this structure will be essentially similar to that of the previously described devices.

From the above description of my invention in connection with three widely different key and space bar actuated mechanisms, it will be evident that I have provided a new combination of counter drive and operating mechanism capable of being readily attached to numerous makes of typewriters, tabulators and bookkeeping machines, of which there are a large number of different types in use, and without the nicety of adjustment hitherto required in locating the counter on the machine relative to the movable machine part for actuating it. Moreover, it will be evident that the marked adaptability of my invention to different machine mechanisms and its ease of attachment are in part due to the novel cooperation between the combined pawl and friction clutch mechanism of the counter and the space or character key operated part of the machine, and in part to the lost motion operating linkage provided for connecting the counter operating lever to these various radically different machine elements. This new combination of counter drive and operating linkage therefor has, so far as the applicant is aware, for the first time enabled a commercially practicable key stroke counter mechanism to be produced for the trade which is of universal adaptability, the counter mechanisms hitherto in use being useless except in connection with a particular machine.

While I have in this application specifically described three forms of my invention, it will be understood that these forms of the same are shown for illustrative purposes, and that the structure may be modified and the invention embodied in other forms without departing from its spirit or the scope of the appended claims.

What I claim as new and desire to secure by Letters Patent is:—

1. Actuating mechanism for a counter applied to a key operated writing machine and having a swinging operating arm element limited in its travel in both directions, said mechanism comprising a transmitting connection between said element and an actuating reversely swinging element of the machine including a transmitting member having lost motion operating relation between it and one of said elements and a resilient member associated with said transmitting member, said connection being operative on movement of said second element in one direction to move said first element yieldingly in one direction through said resilient member from one of its travel limits to the other, with said resilient member permitting overtravel of said second element, and said element which has lost motion operating relation with said transmitting member and said transmitting member being engageable to return said arm element from said other travel limit to said first mentioned limit.

2. Actuating mechanism for a counter applied to a key operated writing machine and having a swinging operating arm element limited in its travel in both directions, said mechanism comprising a transmitting connection between said element and an actuating reversely movable element of the machine including a transmitting

member having lost motion pivotal connection with said key actuated element, and a resilient pull member, said connection being operative on movement of said second element in one direction to move said first element yieldingly in one direction through said resilient pull member from one of its travel limits to the other, with said pull member permitting overtravel of said second element, and said transmitting member being operable by engagement thereof by said second element, on reverse movement of said element, to return said first element from said other travel limit to said first mentioned limit.

3. Actuating mechanism for a counter applied to a key operated writing machine and having a swinging operating arm element limited in its travel, said mechanism comprising a connecting linkage between said arm element and an actuating reversely operated element of the machine, said linkage having a slotted pivotal connection permitting lost motion in the actuation of said arm element in one direction, and a spring interconnecting the parts having said slotted pivotal connection and providing a yielding connection therebetween for actuating said arm element in said direction and permitting overtravel of said second element.

4. Actuating mechanism for a counter applied to a key operated writing machine and having a swinging operating arm element limited in its travel, said mechanism comprising a non-extensible link connected at one end to said arm element and having at the other end a lost motion pivotal connection with a swinging reversely operated element of the machine which provides lost motion longitudinally of said link, and a spring connecting said last named element with said link and providing a yielding pull connection between said link and said last named element.

5. Actuating mechanism for a counter applied to a key operated writing machine and having a swinging operating arm element limited in its travel, said mechanism comprising a connecting member between said element and a reversely movable element of the machine, said last named element having a slot extending substantially longitudinally of said connecting member and into which said member extends, and resilient means connecting said connecting member and said last named element and constantly urging said connecting member into engagement with the remote end of said slot.

6. Actuating mechanism for a counter applied to a key operated writing machine and having a swinging operating arm element limited in its travel, said mechanism comprising a rod pivotally connected to said first named element and having one end pivoted in a slot in a reversely movable element of the machine, said slot disposed longitudinally of said rod, a clip carried on said rod adjacent said last named element having a depending portion through which the pivoted end of said rod extends, and a spring connecting said clip with the adjacent end of said last named element and constantly urging the pivoted end of said rod into engagement with the remote end of said slot and permitting overtravel of said element relative to said rod in one direction while providing for positive operation of said arm element by said rod in the opposite direction.

HARVEY N. BLISS.
